CLAIM

The ornamental design for a yogurt spoon, as shown and described.

DESCRIPTION

FIG. 1 is a perspective view of the yogurt spoon showing my new design;

FIG. 2 is a top plan view of the yogurt spoon shown in FIG. 1;

FIG. 3 is a bottom plan view of the yogurt spoon shown in FIG. 1;

FIG. 4 is a right side elevation view of the yogurt spoon shown in FIG. 1;

FIG. 5 is a left side elevation view of the yogurt spoon shown in FIG. 1;

FIG. 6 is a front elevation view of the yogurt spoon shown in FIG. 1; and,

FIG. 7 is a rear elevation view of the yogurt spoon shown in FIG. 1.

The broken lines shown in the drawings are for illustrative purposes only and form no part of the claimed design.

1 Claim, 4 Drawing Sheets

See application file for complete search history.
